UNITED STATES PATENT OFFICE.

DAVID ROBERTS, OF ANN ARBOR, MICHIGAN.

FENCEPOST-MOLD.

1,388,763.

Specification of Letters Patent. Patented Aug. 23, 1921.

Application filed March 17, 1920. Serial No. 366,607.

To all whom it may concern:

Be it known that I, DAVID ROBERTS, a citizen of the United States, residing at Dexter Ave., (R. 7,) Ann Arbor, in the county of 5 Washtenaw and State of Michigan, have invented certain new and useful Improvements in a Fencepost-Mold, of which the following is a specification.

The invention relates to a mold construction, and more particularly to the class of fence post molds and the fence posts made thereby.

The primary object of the invention is the provision of a mold construction of this 15 character wherein the body thereof is made from a single piece of material cut and folded so as to provide fixed permanently formed channels arranged parallel with each other into which can be poured cementitious material for the shaping of plural fence posts therein, the body of the mold being constructed for the attachment of a leveling board so that the cementitious material can be rendered smooth and level at 20 the open top of the mold on manipulating the smoothing or leveling board which is slidably connected with the body of said mold and at the same time enabling excessive material being relieved from the mold on 25 movement of the board from one end thereof to the other.

Another object of the invention is the provision of a mold of this character wherein opposite side edges of the body thereof are 30 folded on themselves to provide guides with which are engaged cleats carried on a smoothing or leveling board adapted to act upon the contents of the body of the mold for the smoothing of the contents and 35 the finishing thereof prior to the hardening of the cementitious material for the perfect forming of fence posts in the body of the mold, the channels in the body of the mold being smooth so as to eliminate any possibility 40 of the cementitious material sticking thereto or adhering to the surface of the body of the mold during the hardening of the cementitious material.

A further object of the invention is the 45 provision of a mold of this character, wherein one or a plurality of fence posts can be conveniently formed from cementitious material when poured into the body of the mold, the posts formed from said material 50 being rendered smooth and by the use of the

mold the said fence posts can be made with despatch and in an economical manner.

A still further object of the invention is the provision of a mold of this character which is extremely simple in construction, 60 readily and easily made, strong, durable and inexpensive to manufacture.

With these and other objects in view, the invention consists in the features of construction, combination and arrangement of 65 parts as will be hereinafter fully described, illustrated in the accompanying drawings and pointed out in the claims hereunto appended.

In the accompanying drawings:

Figure 1 is a top plan view of a mold constructed in accordance with the invention, showing the smoothing or leveling board mounted thereon and cementitious material partially filling one of the channels in the 75 body of the mold for the production of a fence post.

Fig. 2 is a sectional view on the line 2—2 of Fig. 1 looking in the direction of the arrows.

Fig. 3 is a fragmentary plan view showing a portion of the body of the mold, the same being broken away at intervals.

Fig. 4 is a plan view of the blank from which the body of the mold is made.

Fig. 5 is a plan view showing a slight modification of the mold body for constructing fence posts of tapered formation.

Similar reference characters indicate like or corresponding parts throughout the several views in the drawings.

Referring to the drawings in detail, the fence post mold comprises a body A, preferably made from a blank 10 of sheet metal shown in Fig. 4 of the drawings, the said blank being cut at opposite ends to provide alternate substantially triangular shaped extensions 11 and 12, the extensions 11 being adapted to be folded on crease lines 13, while the blank 10 is provided with spaced parallel crease lines 14 disposed longitudinally thereof for the folding of said blank 10 to provide a plurality of channels 15 in the body A when completed. The extensions 11 when folded on the lines 13 serve as ends to 105 the channels 15 and these extensions 11 being secured in place to close the ends of said channels 15 by the engagement of the flanges 12 with lips or tongues 16 which interlock with the said flanges 12 to provide a folded 110

seam 17 between the extensions 11 and the body A of the blank 10, the folded seams 17 being clearly shown in Fig. 3 of the drawings.

5 The channels 15 in the body A serve as molding spaces for cementitious material when poured therein for the making of fence posts. Formed at opposite sides of the blank 10, that is to say at the opposite side 10 edges thereof are folded flanges 18 constituting guides which are arranged in the same plane with each other for the connection with the body A of a movable smoothing or leveling board 19 which is formed 15 with the reversely tapered opposite ends 20 to the undersides of which are fixed cleats 21 adapted for slidable and detachable engagement with the flanges 18 on the body A of the mold and this board 19 is adapted to 20 slide from one end of the body A to the other for the smoothing of the material contained within the channels 15, the board 19 being manually shifted upon the body A of the mold and in the manipulation thereof the 25 moist material of cementitious substance contained within the channels 15 in said body A can be smoothed and finished at the open top of said body, whereupon when the substance or material becomes hardened the 30 body A will have therein completed fence posts of triangular shape in cross section with perfectly smooth surfaces.

In Fig. 5 of the drawings there is shown a slight modification of mold body, wherein 35 the channels 22 therein are of tapered formation from one end of each to the other so that in the constructing of the cementitious

fence posts the same will have a tapered contour corresponding to the shape of the channel 22, while the channels 15 in the preferred form of the body A of the mold are 40 formed of a size throughout their entire length.

From the foregoing it is thought that the construction and manner of use of the mold 45 and also the production of the fence post will be clearly understood and therefore a more extended explanation has been omitted.

What I claim is:

1. A mold of the character described, comprising a blank of sheet metal cut and bent to form plural longitudinally disposed parallel channels, extensions formed at the ends of the blank and bent to provide end walls to the channels, flanges on said blank, 55 tongues on the extensions and in locking engagement with the flanges, guides longitudinally of the channels and a smoothing board slidably connected with the guides.

2. A mold of the character described, comprising a blank of sheet metal cut and bent to form plural longitudinally disposed parallel channels, extensions formed at the ends of the blank and bent to provide end walls to the channels, flanges on said blank, 65 tongues on the extensions and in locking engagement with the flanges, guides longitudinally of the channels and a smoothing board slidably connected with the guides, and cleats carried by the board for slidably 70 connecting the same to the guides.

In testimony whereof, I affix my signature hereto.

DAVID ROBERTS.
